(No Model.)

C. W. CONKLIN.
SPRING TOOTH HARROW.

No. 416,995.

Patented Dec. 10, 1889.

UNITED STATES PATENT OFFICE.

CALVIN W. CONKLIN, OF AUBURN, NEW YORK, ASSIGNOR TO ALBERT M. NYE, OF SAME PLACE.

SPRING-TOOTH HARROW.

SPECIFICATION forming part of Letters Patent No. 416,995, dated December 10, 1889.

Application filed November 13, 1888. Serial No. 290,698. (No model.)

To all whom it may concern:

Be it known that I, CALVIN W. CONKLIN, a citizen of the United States, and a resident of Auburn, in the county of Cayuga and State 5 of New York, have invented certain new and useful Improvements in Spring-Tooth Harrows, of which the following is a specification.

The purpose of my improvements is to more effectively prevent clogging, to render the 10 draft more easy, to provide improved means for hinging together the sections of folding harrows, and to improve the harrow in other respects, all of which will be hereinafter more fully set forth. I attain these objects by 15 employing means which I will now proceed to describe, making reference in so doing to the accompanying drawings, in which—

Figure 1 is a top view of a harrow embodying my improvements; Fig. 2, a section in the 20 plane of the line $x x$ of Fig. 1, viewed in the direction indicated by the arrow there shown; Fig. 3, a top view of one of the hinges, detached and enlarged; Fig. 4, a section in the plane of the line $x' x'$ of Fig. 3, viewed in the direction 25 indicated by the arrow there shown; and Fig. 5 is a detail, the same being a top view of a hinge and showing a modification in the construction of the same.

Like letters of reference indicate like parts. 30 A A represent sheets or plates of metal, preferably boiler-iron. I deem it best to make these plates, or to use plates, about three-sixteenths of an inch thick and in the form shown; but the thickness and form may be varied. These plates I hinge together after arranging them as shown—that is, so that the front lines of the harrow body, stock, or frame will recede or incline rearwardly as they extend toward the lateral edges or outer ends 35 40 of the said sheets or plates.

B B represent the hinges employed for the purpose referred to, and which I will herein-after more fully describe. I may call attention, however, to the fact that these hinges 45 are applied to the inner or approximately adjacent edges of the said sheets or plates, substantially as shown.

In the plates or sheets A A are holes or openings a a, arranged apart from each other

in substantially regular order; and D D are 50 spring-teeth applied to the upper sides of the said plates by means of clips E E, arranged in front of said openings, through which openings the said springs pass freely, the working ends of the springs being below the said plates, 55 as clearly indicated in Fig. 2.

As my invention does not particularly relate to the construction of the clips employed to secure the springs to the plates, and as any suitable clips may be employed for that purpose, I have not here fully described the construction of the same.

In order to facilitate the drawing or dragging of the harrow, or to enable it to ride easily over obstructions or uneven ground, 65 and thereby lighten the draft, I deem it best, but not absolutely essential, to turn or bend the front edges or portions of the plates A A upward, as is clearly indicated in Fig. 2. To aid in preventing the body or frame from becoming clogged or loaded with loose material, I 70 deem it best, but not absolutely essential, to raise flanges a' a' about the holes a a. The holes b b shown in Fig. 1 are made to receive the bolts which secure the clips to the plates, 75 and the latter may be countersunk, if deemed best, to protect the said bolts from wear.

The hinges B B, I construct as follows, my principal aim being to protect from wear the parts immediately composing the joint or 80 joints of the hinge. I will first describe a two-jointed hinge made to effect this purpose.

c is a block having laterally-extending pins or studs d d thereon, and also a laterally-extending portion d', which is pierced, as 85 indicated at e, Fig. 4, to receive a bolt f.

g is a plate corresponding in form and size to the block c, and this block is pierced to pass upon the studs d d and also to receive the bolt f.

I clamp the parts c and g together by means of the bolt f and a nut h, as is clearly indicated in Fig. 3. It will be observed on reference to Fig. 4 that a space or recess i is thus left between the parts c and g.

G G are arms turning on the pins d d. These arms, as shown in Figs. 1, 3, and 4, terminate at their outer ends in flattened

portions *j j* to facilitate attachment to the plates A A. I desire to state, however, that these hinges need not be so flattened when employed to connect the twin parts or halves 5 of skeleton frames for spring-toothed harrows, or frames made of intersecting bars. In the latter case the bars themselves may be pierced to turn upon the pins or studs *d d*. It will be perceived that the blocks *c*, as well 10 as the plate *g*, shield or protect the parts G G at the joint made by them with the pins *d d*. It will also be perceived that all of the parts constituting the double hinge now described, when used in conjunction with the plates A 15 A, being comparatively small, may be renewed or exchanged for other like parts with facility and comparatively small expense. When, however, the bars of a skeleton frame constitute a part of the said hinge, the said 20 bars will not only be protected from wear, as before stated, but the parts *c* and *g*, when too much worn in offering that protection, may be easily replaced by like parts. It may be here noted that the plates A A themselves 25 will afford protection to the hinges B B, the latter being placed above the former, as shown in Fig. 1.

While I have now described a double-jointed hinge having its joints protected, I 30 desire also to state that a single hinge or joint may in like manner be protected without a substantial departure from my invention. Such a single hinge I have shown in Fig. 5, in which *K* represents a washer 35 clamped upon a bolt passing through the arms G G. In order that this washer may afford this protection from wear to the joint, I arrange it in front of the forward arms G G. I make it of such size and shape that it 40 will extend below, and, if need be, rearwardly and underneath the jointed parts it is intended to protect. It will be perceived that this piece or washer may be readily renewed whenever it becomes too much worn to perform its function. I desire further to say 45 that I regard the part *K* in a single joint as the mechanical equivalent of the parts *c* and *g* in the double joint first herein described.

It will be perceived from the foregoing description that a harrow having a body stock or frame made of sheet or plate metal presents no openings such as exist between the bars of skeleton harrow-frames, and that the clogging permitted by frames of the latter 55 class cannot occur when the former mode of construction is employed. It will also be perceived that the upturned edge or forward portion of the twin plates A A adapt the harrow to ride easily over obstructions somewhat in the same manner as a stone-boat will do. The draft therefore will be light. Some soils, it is well known, require a greater weight than a light harrow furnishes in order to cause the teeth to penetrate the ground sufficiently. 60 Under such circumstances the driver may with comparative safety mount or ride upon

a harrow having a plate-metal body, stock, or frame without other openings in it than are herein shown and described. The frame when constructed of plate metal is not only strong 70 and durable but comparatively light. I believe also that a flat-bottomed frame results in causing the teeth to cut to a more uniform depth, and the frame, if it should ride upon the ground, would leave the ground in a comparatively smooth condition. It will be perceived that if the teeth may be adjusted, as heretofore has been done, in order to cause them to run either deep or shallow, they may also be adjusted to permit the frame to ride 80 upon the ground.

The double hinge herein described permits the twin sides of the harrow to move freely when uneven ground is being worked and when obstructions are met. The harrow may 85 also be folded compactly for transportation. As before stated, these hinges may not only be arranged so as to be protected by the frame, but the construction of the hinge itself is such that the joints are protected from wear; 90 also, by making the hinge in separable parts these parts may be renewed with facility after becoming much worn. I also desire to call attention to the fact that this removable shield may be applied with like effect to 95 hinges having a single joint. I deem it preferable, however, to employ the double hinge, especially on harrows having a frame consisting of the plates A A; but these hinges whenever employed on harrows will tend to 100 hold both sections of the frame together properly and tend to prevent the harrow-teeth from trailing or following each other in the same furrow.

Having thus described my invention, what 105 I claim as new, and desire to secure by Letters Patent, is—

1. A harrow consisting, essentially, of a sheet or plate metal platform having therein the tooth-receiving openings *a a* and bent or curvilinear spring-teeth D D, adjustably applied to the said platform and passing downward through the said openings, substantially as and for the purposes specified.

2. The combination, in a harrow, of a sheet 115 or plate metal platform centrally jointed from front to rear and having therein the holes or openings *a a*, the bent or curvilinear spring-teeth D D, extending downward through the said openings, and clips for securing the said teeth adjustably to the said platform, substantially as and for the purposes specified.

3. A harrow consisting, essentially, of a sheet or plate metal platform having therein the tooth-receiving openings *a a*, having 125 flanges *a' a'* raised about them, and bent or curvilinear spring-teeth D D, adjustably applied to the said platform and passing downward through the said openings, substantially as and for the purposes specified.

4. The combination, with the hinges of a spring-tooth harrow, of a removable or re-

placeable shield or joint-protector for protecting the joint, substantially as and for the purpose specified.

5. As an improved article of manufacture, a spring-tooth-harrow hinge having one or more renewable parts or shields made and arranged for protecting the hinge-joints from wear by attrition with the ground.

Signed at Auburn, in the county of Cayuga and State of New York, this 2d day of November, A. D. 1888.

CALVIN W. CONKLIN.
